[57] **ABSTRACT**

A harpsichord having string plucking means consisting of a vertically moving jack and a plectrum carrying tongue pivotally mounted at the upper end of the jack. A control rod or lever means is associated with each jack and is operated by the same key as the associated jack. The control rod causes the tongue to pivot bringing the plectrum into string plucking position before the jack is raised by the key action. After the string is plucked, the control rod actuating arrangement permits the rod to drop to its rest position before the jack falls thereby preventing the rod from interfering with the retracted position of the tongue and plectrum away from the string, retraction having occurred when the string was plucked. Hence, when the jack drops, neither the plectrum nor its associated buffer contacts the strings until the key is again depressed. Blocking means are provided for holding the plectrum carrying tongue in its rest position when it is desired to use a different register of jacks.

HARPSICHORD WITH SUSTAIN MECHANISM

The present invention relates to string musical instruments wherein the strings are played by a plucking action and more particularly to a plucking mechanism for such instruments which eliminates the restriking of the string on release of the key until the key is again depressed.

In harpsichords or similar instruments, the plucking action of the strings is controlled by keys which are pivotally mounted on the frame of the instrument. Each key controls an individual jack which carries a plectrum at its upper end. When the key is depressed, the jack is raised and the string plucked by the plectrum.

Heretofore, it has been difficult to assure the uniform plucking action of the strings. This is due to a number of factors among which are the appreciable lateral shifting of the strings due to temperature and humidity changes, the movement of a series of jacks which have been shifted out of and into registry with the strings, etc. As a result of such misalignment between the strings and the plectrum, individual plectrums may be closer or further from the strings than desired and plucked too strongly, too weakly, or not at all. If the string has shifted an extreme amount closer to the jack, it is possible for the plectrum to catch on the string, with the jack remaining suspended and inoperative until corrected by manual adjustment. An additional problem present in the string plucking mechanisms is that the plectrum tends to strike the string a second time as the jack moves downwardly to its at rest position. The second striking causes undesirable sound which interferes with the overall musical quality of the instrument and makes a sustaining arrangement unfeasible.

This invention is an improvement in my prior U.S. Pat. No. 3,453,922.

It is the primary object of the present invention to provide a string plucking mechanism for a musical instrument of the harpsichord type in which the plectrum is always correctly aligned with the strings and in which the plectrum is carried well clear of the string when the jack is returning downwardly to its at rest position, thereby avoiding the second striking of the string.

Another object of the invention is to make a sustain action feasible in a harpsichord by eliminating the second striking of the string by the plectrum or its associated buffer even after the jack has dropped to its rest position.

It is also an object of the present invention to provide a string plucking mechanism for a harpsichord or similar instrument in which means are provided for rendering one or more registers of keys inoperative, when desired, and which accomplishes the result without the shifting of the jacks out of their normal position so that misalignment between the plectrum and strings is reduced.

Another object of the invention is to provide an improved tongue positioning means and improved control means for the tongue and hence of the plectrum carried thereby.

A further object of the invention is the provision of a string plucking mechanism for a harpsichord or similar instrument in which the danger of a jack becoming accidentally snagged on a string is eliminated.

The above and other objects and advantages of the invention will become apparent upon consideration of the following specification and the accompanying drawings wherein there is shown a preferred embodiment of the invention.

In the drawings:

FIG. 1 is a fragmentary side elevational view, partially in section, of a key and plucking means associated therewith for a string musical instrument such as a harpsichord;

FIG. 2 is a fragmentary end elevational view of the embodiments of FIG. 1;

FIG. 3 is a fragmentary side elevational view, similar to that of FIG. 1, but showing the key and plucking means at various stages of the plucking action; and

FIGS. 4 and 5 are fragmentary front elevational views of two further modifications of the jack and tongue assembly employed in the present invention.

Referring to FIGS. 1-3, the first embodiment of the invention will now be described. It should be understood that while only one string plucking assembly is shown for clarity of illustration, the harpsichord or other instrument will be provided with additional keys and strings. Also the harpsichord may have more than one register.

The key 12 is pivotally balanced on a balance rail 14 which rests on and is secure to the key bed of the instrument (not shown). The key 12 is received on a positioning pin 16 extending upwardly from the balance rail 14 and rests on a felt washer 18 to allow noiseless pivotal movement. Depressing the front portion of the key 12 causes the rear portion to raise upwardly. Associated with each key 12 there is at least one jack 20 which is received and vertically moveable in openings in guides or rails 22 and 24, suitably supported on the instrument frame. The jack 20 has shoulders 26 which limit its downward movement and hold the lower end of the jack 20 a short distance above the key 12. A cushion 28 is mounted on the top surface of the key immediately below the jack 20. The upper end of the jack 20 is bifurcated as indicated by the reference numeral 30 and a tongue 32 is pivotally mounted within the open portion of the bifurcated end 30. A pin 34 extends through the bifurcated portions 30 of the jack 20 and the tongue 32 to position the tongue. At the upper end of the tongue 30 there is provided an outwardly projecting conventional plectrum 36 for plucking a string 40. A buffer piece 38 of any suitable material such as buckskin, sponge, foam rubber, or plastic is also provided at the upper end of the tongue 32 and on the upper side of the plectrum 36. The upward vertical movement of the jack 20 is limited by a jack or guide rail 42 which has a suitable layer of cushioning material 44 thereon.

A spring member 46 of roughly elongated S-configuration is attached to the opposite side of the tongue 32 from the plectrum 36 and has a curved lower portion 48 which rests on a cushioned upper end 50 of a control rod 52. The rod 52 extends vertically through and is slidable in the support rails 22 and 24 and has projection such as a collar 54 rigidly affixed thereto. As an important feature of the invention, the control rod 52 is operated by means of a roughly Y-shaped lever 56 which is pivotally mounted in a bracket 58 carried by the key 12. The mounting of the lever 56 is accomplished by a pin 60 extending through the bracket 58 and one of the short legs of the lever 56. Another short leg 62 of the lever 56 extends forwardly and a compression spring 64 is retained between the leg 62 and the base of the mounting bracket 58 for adjusting the position of the lever. The outer or upper end 66 of a principal leg 57 of the lever is shown provided with a covering 67 and is normally in contact with the rod 52 and a lower end of the collar 54. The covering 67 is made from any suitable noiseless, wear resistant material, such as leather. A stop member 68, having a pad 70 vertically adjustably carried by a screw 72 extending through a suitable rail 74 of the instrument frame, is provided to aid in control of the lever 56.

As shown in FIG. 3, when the forward end of the key 12 is depressed, causing the rear end thereof to move upwardly, the arm 57 of lever 56 pushes upwardly on the collar 54, causing the control rod 52 to move upwardly. The distance between the lower end of the jack 20 and the pad 28 on the key 12 delays the upward movement of the jack. When the rod 52 is moved upwardly in relation to the jack 20, the spring 46 is pushed upwardly causing the tongue 32 to pivot about the pin 34 bringing the plectrum 36 into string plucking position. As upward movement of the rear end of the key 12 continues, the jack 20 and control rod 52 move upwardly together and the string is plucked by the end of the plectrum 36, the buffer 38 is initially contacting the string 40 to assure that it is properly positioned. Continued upward movement of the key 12 beyond the point at which the string is plucked causes the arm 62 of the lever 56 to strike the pad 70 of the stop 68 and as a result, the lever 56 moves to the position shown in dotted outline of FIG. 3. In this position, the upper end 66 of the lever 56 has been moved clear of the collar 54 and the control rod 52

will move or drop downwardly. The arcuate shape of such lever end 66 and the covering 67 thereon aids in obtaining good but releasable engagement of the lever end with the lower end of the collar 54. The tongue 32 now reacts when the string plucking is terminated to pivot back to its at rest position, removing the plectrum 36 from alignment with the string 40. When the key is released, its lower end moves downwardly, as does the jack 20. However, since the plectrum has moved away from the string, there is no second plucking or contact whatever even after the jack 20 drops to its original rest position and a tone "sustain" is obtained.

In this embodiment, there is also provided a rod 76 which runs the length of a register of keys. The position of the rod or bar 76 may be controlled in any known manner. When this rod is in the position shown in the drawings, normal plucking action of the strings occurs. If, however, the rod 76 is moved to the right so as to push the arm 56 away from the collar 54, the rod 52 is not moved upwardly relative to the jack 20 when the key 12 is depressed and the tongue 32 remains in its at rest position keeping the plectrum clear of the strings so no plucking occurs.

FIGS. 4 and 5 illustrate arrangements for stabilizing the plectrum carrying tongue in the positions to which the operating forces thrust it. In the embodiment shown in FIG. 4, a jack 98, supported by suitable rails and operated by a suitable key, all now shown herein, carries a bifurcated tongue 100 which has a string plucking plectrum, not shown. The tongue 100 is carried by a pin 102 which has a force fit through the tongue 100 and rotated on bushings 104 carried in a bifurcated portion of the jack 98. A spring 106 is secured to the jack 98 and puts pressure against an exposed portion of the pin 102 tending to stabilize the tongue 100 and prevent undesirable movement of the tongue 100 until it is moved by a direct or reactive force.

In the embodiment shown in FIG. 5, a bifurcated tongue 110 is pivotally carried on a pin 112 which has a force fit in the bifurcated ends of a jack 108 and a rotating fit in bushings 114 carried by the tongue 110. In this embodiment, the spring 116 is secured to the tongue 110 and applies pressure against the pin 112 to resist rotation of the tongue 110.

It will be seen that the movement restrictive constructions of FIGS. 4 and 5 set up only small or light forces and still permit pivotal movement on the tongues 100 and 110 by the forces applied thereto or by reaction after a plucking action has been obtained.

It should now be apparent that there has been provided a string plucking mechanism for a harpsichord or a similar instrument which fulfills the objectives set out above. The provision of the pivotally mounted plectrum carrying tongue at the upper end of the jack and of means for biasing the tongue toward the string assures that the plectrum will be properly positioned in relation to the string to cause plucking thereof on upward movement of the jack. The provision of a buffer piece on the upper side of the plectrum also assures that the plectrum is properly positioned with the string so that uniform plucking is achieved. By providing a control rod which operates to bring the plectrum into string plucking position before the jack is raised and which permits the plectrum to remain in a position retracted away from the string while the jack moves downwardly and even after the jack has dropped to its original rest position, assures that the string will be plucked only on upward movement of the jack and thus eliminates the undesired second striking and provides practical "sustain" action for the note provided.

While certain representative embodiments and details have been shown for the purpose of illustrating the invention, it will be apparent to those skilled in the art that various changes and modifications may be made therein without departing from the spirit or scope of the invention.

What is claimed is:

1. In a musical instrument having a frame, a plurality of strings secured to the frame, a plurality of pivotally mounted keys and a plurality of plucking means individually operably

associated with the individual strings and controlled by the keys, each plucking means including a vertically movable jack having a bifurcated upper end, the improvement comprising:

5 a tongue member pivotally mounted to the bifurcated end of said jack by a pin extending through said jack and said tongue member; a plectrum carried by said tongue member and adapted to pluck said string upon upward movement of said jack; and
10 a spring operatively bearing against said pin to aid in retaining said tongue member in the position each positive force applied thereto places it.

15 2. The improvement according to claim 1 wherein said pin is fixedly carried by the bifurcated portion of said jack, said tongue member rotates on said pin, and said spring is secured at one end to said tongue and bears against said pin.

20 3. The improvement according to claim 1 wherein said pin is rigidly mounted in said tongue member and rotatably mounted in said bifurcated portions of said jack, and said spring is secured at one end to said jack and bears against said pin.

25 4. In a musical instrument having a frame, a plurality of strings secured to the frame, a plurality of pivotally mounted keys, and a plurality of plucking means individually operably associated with the individual strings and controlled by the keys, each plucking means including a vertically movable jack, the improvement comprising:

30 a tongue pivotally mounted to the upper end of each jack for movement toward and away from the string associated therewith, a plectrum mounted on said tongue and adapted to pluck said string upon upward movement of said jack;

35 means to urge said tongue toward said string prior to upward movement of said jack, said means permitting said tongue to pivot away from said string after the plectrum has plucked the string and prior to commencement of downward movement of said jack to a position in which said plectrum is offset from said string and to remain in said offset position until said plectrum has dropped below said string whereby a tone sustain action is obtained;

40 said means to urge said tongue includes a spring attached at one end to said tongue, and means contacting the free end of said spring prior to upward movement of said jack to bias said tongue and plectrum toward said string, and being releasable before termination of upward movement of said jack;

45 said means contacting said spring includes a vertical rod the upper end of which contacts the free end of said spring and a lever carried by said key and operably engaging said rod to move said rod upwardly when the front end of said key is depressed; and

50 said lever is pivotally mounted on said key and biased so that the upper end of said lever contacts said rod, said rod having a protruding member secured thereto for engagement by an end of said lever upon movement thereof provided by said key.

55 5. The improvement according to claim 4 further including an adjustable stop engaging and moving said lever to a position clear of said member when said lever has been raised a predetermined distance.

60 6. The improvement according to claim 5 wherein the clearance between said jack and said key is greater than the clearance between said lever and said member whereby said rod is moved upwardly to contact said spring and urge said tongue toward said string prior to upward movement of said jack.

65 7. The improvement according to claim 5 wherein said predetermined distance is sufficiently long that said tongue remains in string plucking position until said plectrum has plucked said string and less than the total upward distance travelled by said jack.

70 8. The improvement according to claim 4 further including a rod movable between a first, inoperative position and a second position in which said rod holds said lever in a position

clear of said protruding member whereby said plectrum carrying tongue remains offset from said string and no plucking action occurs upon vertical movement of said jack.
